UNITED STATES PATENT OFFICE.

WOODBURY D. ROBERTS, OF CENTRALIA, WASHINGTON.

DESIGN FOR A LOCK-CASING.

SPECIFICATION forming part of Design No. 27,609, dated August 31, 1897.

Application filed April 6, 1897. Serial No. 631,035. Term of patent 3½ years.

To all whom it may concern:

Be it known that I, WOODBURY D. ROBERTS, residing at Centralia, in the county of Lewis and State of Washington, have invented and 5 produced a new and original Design for a Lock Case or Frame, of which the following is a specification, reference being had to the accompanying drawing, in which the figure represents a perspective view of my design.

10 The essential feature of my design consists in the ornamental contour of the casing, which embodies a head-like portion having flat upper and lower faces, the external edges of which are represented as being vertical, such 15 head also having portions which terminate in circular ends 2, which merge into straight faces 5, inclined in opposite directions at an obtuse angle to the straight sides 4 4, which extend divergently outward and terminate at

the beginning of the curved portion 6, which 20 form a shank-like representation and which from the point of their beginning are approximately of a circular shape in cross-section.

The inner faces of the shank portion 6 are 25 so curved as to produce an approximately circular opening 7. The upper edge projects slightly beyond the inclined faces 5 5, as indicated at 8.

Having thus described my invention, what 30 I claim is—

The design for a lock-casing substantially as shown and described.

WOODBURY D. ROBERTS.
